(57) **CLAIM**

The ornamental design for a "golf club cover," as shown and described.

DESCRIPTION

My "golf club cover" is characterized by a covering for a golf club head that has one section representing a thumb, a second section representing three folded down fingers, and a third section representing a little finger.

FIG. 1 is a perspective view of a "golf club cover" showing my new design;

FIG. 2 is a front elevation view thereof;

FIG. 3 is a rear elevation view thereof;

FIG. 4 is a bottom plan view thereof;

FIG. 5 is a top plan view thereof;

FIG. 6 is a left side elevation view thereof; and,

FIG. 7 is a right side elevation view thereof.

The broken line representations of a golf club bag and golf clubs in FIG. 1 is for illustrative purposes only and forms no part of the claimed design.
